UNITED STATES PATENT OFFICE.

FREDERICK B. THATCHER, OF PROVIDENCE, RHODE ISLAND.

BOTTLE-STOPPER.

SPECIFICATION forming part of Letters Patent No. 727,711, dated May 12, 1903.

Application filed March 23, 1900. Serial No. 9,864. (No model.)

To all whom it may concern:

Be it known that I, FREDERICK B. THATCHER, a citizen of the United States, and a resident of Providence, in the county of Providence and State of Rhode Island, have invented certain new and useful Improvements in Bottle-Stoppers, of which the following is a specification.

My invention relates to the class of devices adapted to close the mouth of a bottle or like vessel; and the object is to provide a stopper of simple construction with a removable stopple or packing element and of a form which exposes a minimum of non-metallic material to the contents of the bottle.

15 Referring to the drawings, Figure 1 is a view of the top of a bottle, showing a stopper and fastening in side view and closed. Fig. 2 is a view in vertical central section of the top of the bottle and the stopper in the closed position. Fig. 3 is a top view of the stopper on enlarged scale. Fig. 4 is a view in side elevation of the stopper and in section of the stopple or packing on enlarged scale. Fig. 5 is a detail plan view of the packing. 25 Fig. 6 is a detail view of the lower part of the stopper in place and cutting the shank in cross-section.

In the accompanying drawings the letter *a* denotes the upper part of a bottle in connection with which my invention is illustrated, *b* the mouth, and *c* a stopper adapted to close the mouth of the bottle and seal it closely against the leakage of liquids or fluids under pressure.

35 The stopper *c* is made, preferably, of metal, with a cap *d* and a bottom *e* of disk form, united by a small shank *f*, and having a hole *g* in the web *g*, through which the bail of a fastening device passes. This stopper is usually 40 and preferably made of cast metal; but the material and manner of making are immaterial and non-essential features.

It is proposed that the bottom *e* of the stopper shall be of such diameter as to closely fit 45 within the mouth of the bottle, so as to leave the slightest space practicable between it and the surface of the bottle for the leakage of the contents of the bottle, and act as a guide to center the packing.

50 The stopper-fastener is preferably the usual form of U-shaped lever *h*, with the side members *h'* bent to form pivot-bearings *h*² for the

inturned ends of the bail *i*, and the inner ends of the lever are pivoted to the neck-band *k* on diametrically opposite sides, so that the 55 bail in the closed position of the fastener and stopper will hold the latter centrally in place.

The cap *d* of the stopper is less in diameter than the mouth of the bottle, and on the shank *f* a perforated washer *l*, of elastic material, is 60 located, the central opening *l'* through the washer being smaller than the shank *f*, on which it is held, as shown in Fig. 4.

In the closed position of the stopper it is forced down into the mouth of the bottle, so 65 that the edge of the cap *d* draws upon the washer-disk and crowds it inwardly, so that it becomes wedged tightly between the cap and the inner surface of the mouth of the bottle and seals the outlet completely. The 70 packing is large enough in diameter to overlap the mouth of the bottle, and owing to its form and elasticity resists distortions in a manner that causes the part which lies outside of the edge of the cap to contract toward 75 the center of the stopper and at an angle downward toward the bottle, so as to pack closely upon the part of the packing actually located between the edge of the cap and the bottle-mouth. This aids in closing and sealing the bottle.

The washer is attached to the stopper by stretching it on over the bottom part, the material, as india-rubber, permitting the required enlargement of the hole *l'* for this purpose. It is evident that the washer may be renewed as often as desirable, the remainder of the parts being of metal and very durable.

This form of stopper is particularly adapted for use on bottles to hold lager-beer, aerated or so-called "soft drinks," and like beverages bottled under pressure of contained gas. In such beverages it is of advantage to prevent their contact with rubber or like material, which forms the best packing while 90 held in a bottle, and the form of stopper and packing embodying my invention has this advantage in a very great degree, as the metallic bottom of the stopper quite fills the mouth of the bottle in such manner as to prevent 95 the liquid contents from coming into contact with the rubber packing. A further advantage of this form of stopper is that in case of 100 a slight variation in the diameter of the mouth

- of the bottle, which, however, does not detract from the function of the bottom disk *e* as a guide to center the stopper, the packing may be made of varying thicknesses, the 5 thinner one adapted to the smaller bottle and the thickest to the larger, thus enabling the metallic part or base of the stopper to be used to remedy the defects of the slight variations in any given size of bottle-mouth.
- 10 The main advantage in the bottle, however, is the function performed by the bottom *e* as a guide to cause the stopper to be seated centrally in place by the fastening means and to refuse to enter, as it will do, provided the stop- 15 per is so placed as to assume a tilted position from which it cannot recover in entering the mouth. It is found by practice that the stopper unless placed so as to take a central position so as to pack evenly will not enter at 20 all, but will throw off from the edge of the mouth on the application of downward pressure on the bail to seat the device.

What I claim as my invention, and desire to secure by Letters Patent, is—

- 25 1. In combination with a bottle, a stopper consisting of a body part of rigid material having an upper disk and a lower disk each of a diameter practically equal to that of the smallest diameter of the neck of the bottle, 30 said disks being united by a narrow shank, and a disk-shaped packing of india-rubber or like elastic material attached to said shank and to act without obstruction on the edge of the mouth of the bottle, said lower disk-like

portion adapted to occupy that part of the 35 opening into the bottle at or before the packing engages the mouth thereof.

2. In combination with a bottle, a stopper consisting of a body part of rigid material having an upper and lower disk united by a 40 narrow shank, a disk-like packing of india-rubber or like elastic material attached to said shank and adapted to be wedged between the upper disk and the inner surface of the wall of the opening into the bottle and 45 of a diameter to overlap the edge of the mouth of the bottle without obstruction thereof.

3. In combination with a bottle, a stopper consisting of a body part of rigid material having an upper disk and a lower disk each 50 of a diameter practically equal to that of the smallest diameter of the bottle, said disks constituting the greatest diameter of the stopper and united by a narrow shank, and a disk-shaped packing of india-rubber or like elastic material attached to said shank and of a 55 diameter to overlap the edge of the mouth of the bottle and to act thereon without obstruction, said stopper being so constructed that the lower disk-like portion will occupy that 60 part of the opening into the bottle of smallest diameter at or before the packing engages the mouth of the bottle.
